PORTABLE CONTAINER FOR INFANTS'
ACCESSORIES

Dorothy S. Nagy and Louis Nagy, both of 6617 53rd St.,
Sacramento, Calif.

Filed Apr. 12, 1965, Ser. No. 84,741

Term of patent 14 years

(Cl. D87—5)

We claim:

The ornamental design for a portable container for infants' accessories, as shown.
